(57) **CLAIM**

The ornamental design for a puzzle table as shown and described.

DESCRIPTION

FIG. 1 is a perspective view of a main body of a puzzle table, shown separately for illustrating our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the main body of the puzzle table where the main body of the puzzle table is in a first configuration of use;

FIG. 10 is another perspective view thereof;

FIG. 11 is a perspective view of the main body of the puzzle table where the main body of the puzzle table is in a second configuration of use;

FIG. 12 is a perspective view of a rotation member of the puzzle table, shown separately for illustrating our new design;

FIG. 13 is another perspective view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof;

FIG. 19 is a bottom plan view thereof;

FIG. 20 is a perspective view of the puzzle table where the rotation member of the puzzle table is assembled on the main body of the puzzle table;

FIG. 21 is another perspective view thereof;

FIG. 22 is a front elevational view thereof;

FIG. 23 is a rear elevational view thereof;

FIG. 24 is a left side elevational view thereof;

FIG. 25 is a right side elevational view thereof;

(Continued)

FIG. 26 is a top plan view thereof;
 FIG. 27 is a bottom plan view thereof; and,
 FIG. 28 is a perspective view of the puzzle table where the
 puzzle table is in a configuration of use.
 The dash-dash broken lines in the drawings depict portions
 of the puzzle table that form no part of the claimed design.
